DECORTICATING MACHINE.

John S. Reeves, Baltimore, Md.

Application April 9, 1946, Serial No. 660,716.

10 Claims. (Cl. 19—15)

1.

This invention relates to decorticating machines particularly adapted for the production of fiber from the leaves of plants of the Agave family, such as Sansevieria, cabulla, Maya, pita floja, henequen and the like, as well as the members of the Hibiscus family and of the nettle family, such as ramie.

The leaves or stalks of such plants are long and narrow and contain longitudinal fibers which can be recovered by cleaning away the pulp, juice, etc., this waste material being usually called bagasse and the cleaning operation being often referred to as scutching. Although scutching machines as proposed heretofore have varied considerably in design and construction, they have had certain common characteristics. For example, it has been proposed to feed the leaves by hand horizontally and endwise to a rotating scutching wheel at about the level of the wheel axis, the ends of the leaves being bent down over an arcuate scutching surface by the rotating wheel. In larger machines the leaves have been placed on a horizontal feed table or the like where suitable gripping and conveying devices engage one end of the leaf and convey it through the machine while the other end is being cleaned, the cleaned fiber being then gripped and conveyed while the first end of the leaf is being cleaned. The scutching operation in such machines, however, has heretofore been similar to that of the smaller hand machines mentioned above. That is, although the gripped end of the leaf has been dragged axially past a scutching wheel, scutching has been accomplished by bending the free end of the leaf down from the level of the wheel axis over an arcuate scutching surface which extends under the rotating wheel, the scutching surface following the periphery of the wheel and being swept by scutching blades or the like carried by the wheel.

Such automatic feed machines have been of two general types. In one type a single scutching wheel has been provided and each leaf has made two passes through the machine, one end being cleaned by the wheel during the first pass and the cleaned fiber then being lifted and gripped while the other end is turned over to hang down under the scutching wheel during the second pass. The capacity of such machines is limited, and on the other hand complicated elevating, transfer and overturning mechanisms are necessary to interchange the ends of the leaf with respect to the scutching means.

A modification of the above type of machine has been proposed in which a second scutching

2.

wheel has been located along the path of travel of the leaves beyond the elevating, gripping and overturning devices. For example, two wheels have been located at spaced points in a circular path of travel provided by a rotating wheel, moving chain, etc.

Another type of machine has been proposed in which it is not necessary to interchange the ends of the leaf. Two scutching wheels are spaced apart along and located on opposite sides of the center line of the machine, the path of travel of the centers of the leaves being along this center line with the leaves lying lengthwise across the direction of movement. These wheels rotate in opposite directions, the periphery of each wheel moving inwardly toward and downwardly past said path of travel. The leaf is gripped on one side of the center line and conveyed past the first wheel at about the level of its axis, at least half of the leaf at its free end being bent down over the scutching face and under the wheel on the other side of the center line. The cleaned fiber leaving the first wheel is then elevated to about the level of the second wheel axis and gripped by a second conveying means which conveys the leaf past the second wheel with its other end bent down over the scutching face on the first side of the center line.

A serious fault common to machines of the several types described above has been their tendency to break the fibers. It will be seen that each leaf must be bent substantially at a right angle when its end is bent down over the scutching face. These leaves are fairly stiff and when bent at a sharp angle some of the fibers are broken in two at the bend. Further breakage of the fibers at the bend or elsewhere is caused by the downward beating and pulling stroke of the rapidly moving scutching blades along the depending end of the leaf. Broken fibers are stripped away with the bagasse, or at best leave the wheel with the remaining unbroken fiber in the form of loose, unattached relatively short pieces of little value. The broken fibers remaining in the other end of the leaf also become loose unattached pieces and many of them are carried away with the bagasse in the second scutching operation.

Machines embodying the present invention correspond more closely to the last mentioned type of prior machine, in that they comprise automatic feeding means together with a pair of scutching wheels spaced along the path of travel of the center portions of the leaves, i. e., the center line of the machine, the wheels rotating in opposite directions and operating in succession on the oppo-

site ends of the leaves. In other respects, however, the invention departs radically from prior practice as pointed out below.

One of the main objects of the invention is to prevent practically completely the breakage of fiber that takes place as set forth above, and thus to increase the yield of the machine and the production of full length fibers.

Another object is to feed the leaves through a machine which scutches the two halves in succession without sharp or abrupt bends in the leaves.

A further object is to maintain the length of the fibers substantially in line with the direction of the scutching pull, avoiding sharp corners over which the fibers might be broken easily.

Still another object is to provide novel scutching means such that fiber breakage is prevented while at the same time handling of the leaves is facilitated and complicated elevating and transfer mechanisms are eliminated.

Still further objects are to provide a smaller, more compact and simpler scutching machine of equal or greater capacity and of more satisfactory and more efficient operation than scutching machines as previously proposed.

Other objects will appear more fully herein-after as the description of the invention proceeds.

Machines embodying the invention, generally described, comprise a pair of scutching wheels spaced apart in the direction of the travel of the leaves and rotating in opposite directions, but substantially coaxial instead of being located on opposite sides of the path of travel of the centers of the leaves. This path of travel, instead of being located at about the level of the axes of the wheels, is in a horizontal plane extending over the tops of the wheels, and each wheel rotates outwardly and downwardly under one end of the leaf and away from its center in a curved path. Arcuate scutching plates are then inverted over the upper portions of the wheels, extending away from the center line of the machine in opposite directions corresponding with the directions of rotation of the wheels.

Thus at each wheel the free half or more of the leaf that is to be cleaned extends from the gripping and conveying devices substantially horizontally over the top of the wheel and then in a gentle curve over its upper periphery, the leaf being scutched against the underneath side of the inverted scutching plate. In effect the leaves are supported at or near their centers and their ends permitted to droop in gradual curves conforming to the circumferences of their wheels, the rate of curvature depending on the radii of the wheels which can be selected as desired. Actually, of course, each leaf is first gripped somewhat to one side of its center and then the cleaned fiber is gripped somewhat to the other side of the center so that the successive scutching operations cover the center. However, the difference in elevation between these gripping points is so slight that no special elevating mechanism is required for the cleaned fiber, it being sufficient merely to provide off-set conveyors which overlap axially with their overlapping ends inclined downwardly as hereinafter described. These conveyors, together with suitable stationary leaf supports leading to and from the respective wheels, carry the leaves automatically through the machine without sharp bending or breaking, the scutching pull being exerted longitudinally

of the fibers without breaking them over sharp corners.

One embodiment of the invention has been illustrated in the accompanying drawings, but it is to be expressly understood that said drawings are for purposes of illustration only and are not to be construed as a definition of the limits of the invention, reference being had to the appended claims for this purpose.

In the drawings,

Fig. 1 is a side view of the complete machine;

Fig. 2 is a plan view of the machine;

Fig. 3 is a view of the entrance end of the machine;

Figs. 4 and 5 are detail sections on the lines 4-4 and 5-5 of Fig. 2;

Figs. 6 and 7 show respectively the first and the second conveying means; and

Fig. 8 is a diagrammatic perspective view illustrating the manner of supporting the leaves as they are conveyed through the machine.

The machine may have any suitable supporting frame, as for example one built up by riveting or welding. In the form shown, the machine rests on a bed plate 1 and the frame structure comprises four parallel vertical transverse partitions 2, 3, 4 and 5 which are rigidly connected in any suitable manner as by horizontal flanges 6 midway in the height of the machine, etc. The partitions 2 and 5 enclose the moving parts of the apparatus at both ends and preferably the lower part of the machine below the flanges 6 is further enclosed by side plates secured to the transverse partitions. Above the flanges 6 the moving parts of the machine are sufficiently housed and shielded by the leaf supporting means, etc., herein-after described in detail.

The machine comprises two scutching wheels 7 and 8 which are spaced axially and arranged to rotate in opposite directions on substantially coaxial horizontal axes. In the form shown, the wheel 7 is mounted on a shaft 9 which extends through the partitions 2 and 3 and is carried in bearings 10 supported by the flanges 6. The wheel 8 is similarly mounted on a shaft 11 which extends through the partitions 4 and 5 and is carried in bearings 12 supported by the flanges 6.

Any suitable means may be employed for driving the wheels 7, 8 in appropriate and opposite directions. In the form shown, wheel 7 is assumed to rotate in a clockwise direction as viewed from the left-hand end of the machine, whereas wheel 8 rotates in the opposite direction. Wheel 7 is driven by a pulley 13 on the end of its shaft 9 and by a belt 14 running from the pulley 13 to a pulley 15 on a drive shaft 16, this shaft being driven in the appropriate direction by means of a belt 17. The wheel 8 is similarly driven in the opposite direction by a pulley 18 on its shaft 11 and by a belt 19 running from the pulley 18 to a pulley 20 on a drive shaft 21, this shaft being driven in the appropriate direction by means of a belt 22. Each of the wheels may be provided with scutching blades 23 of any suitable type as illustrated in Figs. 4 and 5.

The leaves are conveyed through the machine and in succession over the two scutching wheels 7 and 8 by suitable conveying devices which engage the leaves adjacent their centers as herein-after described. The direction of movement of the leaves is assumed to be from left to right as seen in Figs. 1 and 2. During this travel the ends of the leaves are prevented from hanging down from the conveyors, and are carried through

the machine and fed to the scutching wheels, by leaf supporting means having a generally cylindrical configuration of approximately the same curvature as the peripheries of the rotating wheels. This supporting means preferably includes a feed table at the entrance end of the machine and plates or equivalent supporting devices between the partitions 2, 3, 4 and 5, the partitions being slotted for passage of the leaves. Curved plates are preferred as leaf supporting means, because they form continuous supports and constitute at the same time housings or shields for the rotating scutching wheels and associated parts. A preferred form of this leaf supporting means is shown diagrammatically in Fig. 8 and is described in detail hereinafter.

The feed table preferably has the configuration shown in Figs. 1, 2, 3 and 8. The outer end 24 of the table is flat throughout its entire width transversely of the machine, but on both sides of the center line of the machine, the table curves downwardly at its edges as it approaches the end partition 2, thereby providing curved or arcuate side sections 25 and 26. These side sections are preferably connected by an intermediate portion 27 the configuration of which is such as to merge into the two side sections. Preferably the entire table top is made of a single sheet of metal bent to the desired shape, but it may be made in sections if desired.

The table may be supported in any suitable manner, being shown as attached to the end partition 2 and carried at its outer end by vertical supports 28. The latter are connected to gratings 29 one of which is preferably provided at each side of the table for the operator or operators of the machine. The gratings are connected to the partition 2 and braced by angles 30.

The leaves may be moved along the feed table by hand, but preferably suitable conveyors are provided in the form of parallel belts 31 running around sprockets 32, 33 and provided if desired with projecting studs or pins 34 (Fig. 6) for better engagement with the leaves. The sprockets 32 are carried by a supporting frame 35 which projects outwardly from the end partition 2, and the sprockets 33 are carried by a bracket 36 beneath the outer end of the table which bracket is braced by an arm 37 extending to the lower part of the frame 35.

The belts 31 are offset to one side of the center line of the machine so that they support a leaf to one side of its center. As the belts approach the end partition 2, the table drops away underneath them due to the curvature of the side sections 25, 26. The section of the leaf between the belts, however, is self-sustaining and is carried forward to the conveying means hereinafter described at about the level of or slightly above the tops of the scutching wheels (see Fig. 6). Just before the leaf reaches the end partition 2, it is engaged and gripped between the belts 31 by said conveying means and thereby conveyed through openings in the partition and past the first scutching wheel 7. As this wheel is assumed to be rotating clockwise when viewed in the direction of travel of the leaves, it will clean the right-hand end of the leaf.

The external shape of the partition 2 is not of great importance, but it preferably extends upwardly far enough to provide complete enclosure for the wheel 7 and is provided with a feed slot or opening through which the leaf passes. The right-hand portion 38 of the feed slot has a curved inner edge concentric with the wheel 7 and of

such a radius as to expose the rotating scutching blades 23, the curved table section 25 having the same radius and being supported on this inner edge. An arcuate scutching plate 39 is secured against the outer edge of the slot and around the periphery of the wheel, said scutching plate preferably extending somewhat through the slot and projecting in advance of the partition 2 as shown at 40. A slot 41 similar to the slot 38 is formed in the second partition 3 on the other side of the wheel, the scutching plate 39 extending between these partitions and being suitably secured in the slots. As shown in Fig. 4, the slots 38, 41 and the scutching plate 39 preferably extend circumferentially over the top of the wheel and slightly to the left of the center line of the machine, so that the leaf is cleaned beginning at a point slightly to the left of the center line. The scutching plate 39 also serves as a shield or housing between the partitions 2, 3 which encloses the rotating wheel. Beyond the lower ends of the slots, a suitable shield 42 extends on to the flanges 6.

The left-hand portion 43 of the entrance slot 25 in the partition 2 is also curved concentrically with the wheel but the radius of the inner edge is great enough to cover the rotating blades 23. The curved side section 26 of the feed table has the same radius and is supported on this inner edge. A similar slot is formed in the second partition 3, and a curved plate 44 extends between the inner edges of these slots, thereby forming a continuation of the side section 26 which carries the end of the leaf over the top of the wheel 7 on the left-hand side of the machine and at the same time houses the rotating wheel between the partitions 2 and 3. Below the ends of the slots, the plate 44 may be continued if desired by a shield 45 which extends on to the flanges 6.

The slot portions 38 and 43 are connected by an intermediate slot portion 46 to provide a continuous opening for the full length of the leaf, the conveying means hereinafter described passing through this intermediate slot portion. Thus a leaf which is placed flat on the end of the feed table is moved up to the partition 2 and through the continuous feed opening 38, 46, 43 in the position shown in Fig. 4. The left-hand end of the leaf is carried through the slot 43 and over the wheel without cleaning by the table section 26 and support 44. The right-hand end of the leaf is carried along the table section 25 and through the slot portion 38 to the rotating scutching blades 23 which lift it against the scutching plate 39 and clean it as it passes between the blades and the scutching plate. As shown in Fig. 4, there are no sharp bends in the leaf and the pull of the scutching blades is exerted longitudinally of the fibers without breaking them over sharp corners or edges.

The partitions 4 and 5 which enclose the second wheel 8 are preferably the same as the partitions 3 and 2 respectively but reversed with respect to the sides of the machine. Thus partition 4 has a right-hand slot portion 47 corresponding to the left-hand slot portion 43 of partitions 2 and 3, or in other words at a greater radius than the right-hand slot 41 of partition 3 from which the cleaned fiber emerges. Hence a leaf support 48 is provided between partitions 3 and 4 which carries the cleaned fiber between these partitions and at the same time moves it radially outward. Preferably this support 48 comprises a section of a conical surface extend-

ing from the inner edge of slot 41 in partition 3 to the inner edge of slot 47 in partition 4. The support 48 also serves as a shield or housing between these partitions.

Partition 5 has a right-hand slot portion 49 corresponding to the slot 47 in partition 4, and between these partitions the cleaned fiber is carried over the wheel 8 by a curved support 50 similar to the support 44 and extending from the inner edge of slot 47 to the inner edge of slot 49. The cleaned fiber passing through slot 49 and beyond the partition 5 may be carried for a suitable distance on a support 51 which is integral with or a continuation of the support 50.

The left-hand slot 52 of partition 4 corresponds to the right-hand slots 38 and 41 of partitions 2 and 3, and the uncleaned left-hand end of the leaf which emerges from partition 3 is carried to partition 4 by a conical support 53 that is the reverse of the support 48. In other words, support 53 extends from the inner edge of the slot in partition 3 to the inner edge of the slot 52 in partition 4 which is of less radius to expose the rotating scutching blades of the second wheel. The conical support 53 thus allows the uncleaned left-hand end of the leaf to move radially inward as it travels axially between partitions 3 and 4, whereby this end of the leaf is fed to the second scutching wheel in the same manner as described above with reference to the right-hand end. In passing between partitions 4 and 5, this left-hand end of the leaf is cleaned against an inverted arcuate scutching plate 54 similar to the scutching plate 39, and the cleaned fiber emerging from partition 5 is preferably carried on beyond the partition for a suitable distance by means of a curved support 55. Preferably a grating 56 similar to the gratings 29 is provided at the discharge end of the machine this grating 56 being supported by braces 57.

Figs. 4, 5, 6 and 7 illustrate in detail suitable conveying mechanisms whereby the leaves are moved through the machine as described above. There are two of these conveyors, one passing the first wheel 7 on the left-hand side of the center line of the machine as shown in Figs. 2 and 4 and the other passing the second wheel 8 on the right-hand side of the center line as shown in Figs. 2 and 5. Each of these conveying mechanisms preferably comprises two continuously moving elements between which the leaf is gripped under pressure. These elements may take various forms, such as chains or belts or a combination of both, and preferably the lower element is supported and the upper element is held downwardly against the lower element by spring pressure. Referring to Figs. 4 and 6, the lower element of the first conveyor comprises a chain 58 the links of which carry plates or pads 59 forming a more or less continuous surface. This chain 58 passes over a sprocket 60 which is mounted on the frame 35 in advance of the partition 2 and between the sprockets 32 of the belts 31, all of these sprockets being preferably on the same shaft. The chain travels horizontally from sprocket 60 in the direction of feed of the leaves at a level just slightly above the circular path of travel of the outer edges of the scutching blades 23 as clearly shown in Fig. 4. The horizontal reach of the chain is supported by a rail 61 which begins at a point close to the sprocket 60 and continues through the partitions 2 and 3. The rail is provided with channels 62 along each edge in which are mounted rollers 63 on which the chain pads

59 ride as shown in Fig. 4. The rollers may be lubricated by oil pipes 64. Between the partitions 2 and 3, the rail 61 may be cut away on one side as shown at 65 (Fig. 4) in order to bring it down closer to the scutching wheel without interfering with the rotation of the scutching blades. This is desirable in order to have as little bending in the leaves as possible, while keeping the chain 58 in toward the center line 10 of the machine.

The rail 61 is supported in any suitable manner, preferably resting in corresponding notches 66 in the partitions 2 and 3 (Fig. 8) and on associated brackets 67 (Fig. 6). Beyond the partition 3, 15 the end 68 of the rail curves downwardly for a purpose hereinafter stated, this end of the rail being supported by an arm 69. Preferably a belt 70 runs on top of the chain pads 59.

Thus the left-hand part of the leaf is supported near its center by the horizontal reach of the chain and belt as it moves over the first scutching wheel, the end of the leaf being supported by the table section 26, the support 44 and the support 53 as described above. It is desirable 20 to convey this end of the leaf positively well past the partition 3 to make sure that the cleaned fiber at the other end, which tends to lag behind, is positively engaged by the second conveying means described hereinafter. It is also desirable 25 to make sure that the left-hand end of the leaf is fed properly to the second scutching wheel. Hence the chain 58 and belt 70 are continued beyond partition 3 to partition 4, overlapping the second conveying means as described below. As 30 the end of the leaf approaches the slot 52 in partition 4, the chain and belt run downwardly over the curved end 68 of the rail 61 and then over a roller 72 mounted on a bracket 73 secured to the partition 4. This roller is preferably so located 35 that the chain and belt run slightly through the partition 4 just below the inner edge of the slot 52 and then downwardly in an inclined direction that takes them back through the partition in the reverse direction, the chain and belt running 40 in a vertical slot in the partition and carrying the end of the leaf into and through the feed slot 52.

From roller 72 the chain and belt pass downwardly around a drive sprocket on a cross shaft 74, thence horizontally to a sprocket 75 mounted 45 at the bottom of the frame 35, and thence upwardly to the sprocket 68 as described above.

The upper conveyor element preferably comprises a similar combination of chain and belt that is arranged for assembly as a unit and installation on or removal from the machine as a unit. To these ends the upper edges of the partitions 2 and 3 are slotted vertically (Fig. 8) to receive the upper unit which is carried by a plate 76 having 50 depending arms 77 adjustably bolted at 78 to partitions 2 and 3 on both sides of the slots. The vertical position of the plate 76 can be determined by adjusting screws 79 which engage the top edges of the partitions 2 and 3 and are adjusted before the bolts 78 are secured. Thus the entire 55 upper unit can be installed or removed as a unit.

The lower reach of the upper chain and belt is pressed down by suitable resilient means against the upper reach of the lower chain and belt that is supported by the rail 61 as described above. In 60 the form shown, the upper conveyor element comprises a chain 80 passing around an idler sprocket 81 at one end of the plate 76 and a drive sprocket 82 at its other end the plate having 65 openings in which the sprockets rotate and through which the chain passes. Sprocket 82 is

driven by a shaft 83 as hereinafter described. The links of the chain 80 carry plates 84 and pads 85 which are resiliently mounted on the plates 84 by means of stud bolts 86 and springs 87. The lower reach of the chain travels under a rail 88 provided with channels 89 and rollers 90 similar to the corresponding elements of the lower rail 61 previously described, the chain pads 84 riding under the rollers 90. This rail 88 is adjustably mounted on the plate 76 as for example by means of brackets 91 between which bolts 92 are pivoted, these bolts extending through plate 76 and being locked in adjusted position relative thereto by means of nuts 93. A belt 94 runs around the chain pads 85 so that the leaves are gripped directly between the lower belt 70 and the upper belt 94 as shown in Fig. 4, these belts being pressed together by the springs 87 with a force that depends upon the adjusted position of the rail 88.

Near the end of this conveying means, where the lower chain 58 travels downward over the curved end 68 of the rail 61 as described above, the upper belt 94 is preferably arranged to follow this curvature so as to continue the gripping and conveying of the end of the leaf up close to the partition 4. To this end the belt 94 separates from the chain pads 85 and travels around a roller 95 mounted on the plate 76 by means of an arm 96, and thence around a second roller 97 mounted on the plate 76 by means of an arm 98 and back to the upper reach of the chain. As shown in Fig. 6, the position of the roller 95 is such that the belt 94 does not follow the chain pads 85 up around the sprocket 82, but continues on with the belt 70 and follows it part way around the curved end 68 of the lower rail 61.

Any suitable means can be provided for driving the upper and lower conveyor units at the desired speed. In the form shown, a belt 99 runs from a pulley on the end of the shaft 9 of the scutching wheel 7 to a pulley on the input shaft 100 of a suitable gear box 101, the output shaft 102 of which drives a chain 103 running to the drive shaft 74 mentioned above. The lower chain 58 and its associated belt 70 are driven in this manner. The drive shaft 83 of the upper chain 80 and belt 94 is located vertically above the drive shaft 74 between the partitions 3 and 4, its outer bearing 104 being carried by brackets 105 secured to the partitions (Fig. 3). These drive shafts are connected by a cross belt 106 so that the shafts are driven in opposite directions. It may be noted that in passing around the sprocket 68, the lower chain 58 drives the sprockets 32 and the belts 31 at the same speed as the chain.

As explained above, the cleaned fiber at the right-hand end of the leaf leaves the scutching wheel 7 and emerges from the partition 3 where it is engaged by a second conveying means which conveys the leaf past the second scutching wheel 8. Preferably this second conveying means comprises upper and lower units as in the case of the first conveying means, but the second conveying means is located on the right-hand side of the center line of the machine as shown in Figs. 2, 3 and 5 and begins at or near the partition 3 where it receives the cleaned fiber leaving the first wheel 7. In the form shown, the details of construction of the second conveying means are like those of the first conveying means and will be understood from the above description and hence a general description of the second conveying means will be sufficient.

Referring particularly to Figs. 5 and 7, it will

be seen that the lower conveying element of the second conveying means comprises a chain 107 and belt 108 traveling on a supporting rail 109. This rail has a curved end 110 corresponding to the end 68 of the rail 61, except that the ends of the rails are reversed. The second conveying chain and belt moves upwardly in a slot in the partition 3 to a roller 111 corresponding to the roller 72, and thence over the curved end 110 of the rail 109. Thus the chain and belt are located just under the slot 41 from which the cleaned fiber emerges to drop on the conveyor, the ends of the fibers being supported by the curved plate 48 described above.

The upper conveyor element comprises a chain 112 held down by an adjustable rail 113 and carrying plates 114 and pads 115 with interposed springs 116 or the like. A belt 117 runs along the upper reach of the pads 115, this belt then passing around rollers 118 and 119 and the latter being located in a position corresponding to that of the roller 95. Thus belt 117 engages the lower belt 108 close to the partition 3 and follows the lower belt up the curved end 110 of the rail 109. The cleaned fiber emerging from the partition is lifted by the lower belt and also dragged up by the first conveying means which is still pulling the other end of the leaf ahead. After only a short movement insured by these means, however, the cleaned fiber is engaged positively between the upper and lower belts 117 and 108 and is thereafter carried horizontally between the upper and lower conveyor elements past the second scutching wheel 8, the free ends of the fiber being carried over the wheel by the plate 50. Since the cleaned fiber is somewhat more difficult to hold than the uncleared end of the leaf, it may be desirable to provide the belts 108 and 117 with a special configuration better adapted to hold the fiber against the transverse pull of the scutching wheel. In the form shown, the lower belt 108 is relatively narrow as compared with the upper belt 117, and the latter is provided with marginal ribs 120 or the like (Fig. 5) which straddle the lower belt.

As stated above, the cleaned fiber at the right-hand end of the leaf lags somewhat behind the left-hand end of the leaf as it leaves the first scutching wheel 7, and unless this lag is connected there will be a tendency for the left-hand ends of the leaves to jam up at the second scutching wheel. Hence the second conveying means is preferably driven at a greater speed than the first conveying means in any suitable manner. In the form shown, the lower chain passes over an idler sprocket 121 and down to a second idler sprocket 122 both mounted on a frame 123 carried by the end partition 5. The chain, now joined by the belt 108 as explained below, then passes to a drive sprocket on a drive shaft 124 and thence up to the roller 111 and on as described above. Shaft 124 is driven by a chain 125 from the output shaft 126 of a gear box 127, the input shaft 128 of which is driven by a belt 129 from the drive shaft 21 referred to above. Thus drive shaft 124 of the second conveyor is driven separately from drive shaft 74 of the first conveyor and their relative speeds can be adjusted as desired. The drive shaft 124 is connected by a crossed belt 130 with a shaft 131 on which the drive sprocket 132 of the upper conveying element is mounted, the outer end of shaft 131 being supported in a bearing 133 carried by brackets 134 on the partitions 3 and 4. It will be understood that the sprocket 132, as well as an idler sprocket

135 at the other end of the upper chain, are carried by the plate 136 corresponding to the plate 76 of the first conveying means.

Preferably the belts 108 and 117 are arranged to serve as means for discharging the cleaned fiber from the machine after it emerges from the partition 5 onto the supports 51 and 55. Both belts pass over a roller 137 whereby the lower belt is separated from the lower chain 107 and the two belts caused to follow the upper chain part way around its idler sprocket 135 as shown in Fig. 7. The roller 137 may suitably be mounted on an arm 138 connected to the frame 123 mentioned above. From roller 137 both belts pass outwardly and downwardly for a substantial distance to carry the cleaned fiber positively out of the machine while it is still gripped between the belts. When this action has been continued far enough, the upper belt 117 passes upwardly around a roller 139 and thence around a roller 140 from which it returns to the upper reach of the upper chain, both of these rollers and the rollers 118, 119 forming part of the assembly carried by the plate 136. The lower belt 108, however, continues outwardly and downwardly to a roller 141 carried by arms 142 extending from the frame 123, thus carrying the clean fiber out to the discharge end of the machine. From the roller 141 the belt 108 passes down and back to the lower chain at the sprocket 122.

The bagasse discharged at the bottom of the machine is carried away by suitable transverse conveyors, one under each wheel, which can be driven in either direction and either in the same or in opposite directions as may be desired. In the form shown, a transverse drive shaft 143 is located at the bottom of the machine below the drive shaft 124 and driven from it by a chain 144. A bevel gear 145 on shaft 143 drives a bevel gear 146 on a longitudinal shaft 147 which carries drive pulleys 148 and 149 for conveyor belts 150 and 151 respectively. These conveyors pass transversely under the wheels 7 and 8 respectively to idler pulleys 152 and 153 respectively at the other side of the machine. The direction of movement of the conveyors depends upon whether the bevel gear 146 is at the left or at the right of the bevel gear 145 as seen in Fig. 1.

The operation of the machine will be clear from the foregoing description and may be briefly summarized as follows. Leaves to be cleaned are placed across the feed table and carried forward by the belts 31 with their ends drooping over the curved side sections 25 and 26 of the table. As a leaf nears the end partition 2, it is gripped between the belts 31 by the first conveying means and carried through the entrance slots in the partition and past the first wheel 7. The left-hand end of the leaf is carried over this wheel, while the right-hand end of the leaf passes between the scutching blades 23 and the scutching plate 39 as shown in Fig. 4. The leaf is thus cleaned throughout slightly more than half of its length at its right-hand end, but without any abrupt or sharp bending, the pull of the scutching blade being exerted longitudinally of the fibers without bending them over sharp corners.

Between the intermediate partitions 3 and 4, the left-hand end of the leaf is carried positively forward by the first conveyor while it is also moved radially inward so as to pass under the second scutching plate. This feeding action is continued right up to the partition 4.

Meanwhile the cleaned fiber at the right-hand

end of the leaf is engaged by the second conveyor and moved ahead with its free end resting on the support 48. At the same time this cleaned end of the leaf moves radially outward far enough to pass over the second wheel on the support 50. Also the second conveyor moves substantially faster than the first conveyor so that the right-hand fiber end of the leaf catches up with the uncleaned left-hand end of the leaf substantially as the leaf passes through the partition 4 and is released by the first conveyor. Thereafter the leaf is dragged past the second wheel by the second conveyor while the left-hand end is being cleaned as shown in Fig. 5, again without sharp bends in the fiber.

The cleaned fiber emerging from partition 5 is carried to discharge by the belt 108. The bagasse is discharged by the wheels 7 and 8 on the conveyors 150 and 151 and thereby conveyed to waste.

Each leaf is thus carried through the machine supported near its center and with its ends drooping somewhat but in a gradual curve. There is no material change in the configuration of the leaf throughout, the only variation being that each end in succession is caused to move radially inward just enough for it to pass under the respective inverted arcuate scutching plates. Thus no material bending of the fibers takes place and breakage of fibers is minimized. No overturning or interchanging mechanism is required, and the leaves pass automatically through the machine at a relatively high rate, with correspondingly large capacity.

By mounting the two wheels coaxially, the lateral dimensions of the machine are substantially reduced. The wheels are completely enclosed, and the upper conveyor elements are at the top of the machine close to the center line and remote from the operators, so that the danger of accident and injury to the operator is reduced to a minimum. The machine is completely automatic in operation, and once assembled there are no mechanisms to get out of adjustment and require shutdowns and servicing.

While only one embodiment of the invention has been illustrated in the drawings, it will be understood by those skilled in the art that the invention is not restricted to this embodiment, but is susceptible of a variety of mechanical expressions, and also that various changes may be made in the form, details of construction and arrangement of the parts, all without departing from the spirit of the invention. Reference should therefore be had to the appended claims for a definition of the limits of the invention.

What is claimed is:

1. A machine of the class described comprising two upright scutching wheels rotating in opposite directions one behind the other, an arcuate plate over each wheel and extending around the wheel in the direction in which the wheel rotates, the underneath surfaces of said plates comprising scutching surfaces substantially concentric with their respective wheels, means above each wheel at a point in its rotation ahead of said scutching surface for holding materials to be cleaned, means for moving said holding means past their respective wheels in an axial direction, and supporting means comprising a feed table in advance of the first wheel on which said materials are placed to be engaged by said first holding means, said table terminating adjacent the face of said first wheel in an arcuate surface substantially concentric with but of less radius

than the first scutching surface, said supporting means comprising a section forming a continuation of the feed table over the other side of the first wheel and terminating adjacent the face of the second wheel in an arcuate surface substantially concentric with but of less radius than the second scutching surface, said supporting means further comprising a section receiving the cleaned ends of said materials from the first scutching surface and carrying them over the second wheel on the side thereof opposite to the second scutching surface.

2. Green decorticating apparatus of the class described comprising two upright scutching wheels rotating in opposite directions one behind the other, stationary arcuate plates one substantially concentric with each wheel and extending around its wheel in the direction of rotation thereof, each wheel having axially extending blades the edges of which are substantially parallel to and spaced closely from the underneath surface of the associated plate, whereby materials to be cleaned are forced against said underneath surfaces and scutched by said blades, stationary supports for said materials one extending relative to each wheel in the direction opposite to its plate, the upper surfaces of said supports being located at a greater distance from the axis of the machine than said underneath surfaces, inclined material supports each extending axially between said wheels from a point below one of said underneath surfaces up to the level of the axially aligned support, and means for conveying said materials through the machine past said wheels in succession, said materials at each wheel being partly carried by its support and partly scutched against the underneath surface of its plate.

3. Apparatus as defined in claim 2, comprising a feed table in advance of the first wheel terminating at said first wheel in a section corresponding with the stationary support and another section that is arcuate and concentric with but of less radius than the scutching surface.

4. Green decorticating apparatus of the class described comprising two upright scutching wheels rotating in opposite directions one behind the other, stationary arcuate plates one substantially concentric with each wheel and extending around its wheel in the direction of rotation thereof, each wheel having axially extending blades the edges of which are substantially parallel to and spaced closely from the underneath surface of the associated plate, whereby materials to be cleaned are forced against said underneath surfaces and scutched by said blades, stationary supports for said materials one extending relative to each wheel in the direction opposite to its plate, the upper surfaces of said supports being located at a greater distance from the axis of the machine than said underneath surfaces, inclined material supports each extending axially between said wheels from a point below one of said underneath surfaces up to the level of the axially aligned support, and separate conveying means each moving said materials past one wheel, said conveying means being offset

laterally and each extending axially over the support at its associated wheel.

5. Apparatus as defined in claim 4, each of said conveying means comprising a pair of endless conveyors having parallel reaches between which said materials are gripped and conveyed, at least one conveyor of each pair comprising a series of pads individually and resiliently mounted to accommodate irregularities in the thickness of said materials and an outer flexible continuous belt-like member extending around and moving with said pads.

6. Apparatus as defined in claim 5, together with means for pressing one of said parallel reaches toward the other and means for supporting said other reach against the pressure.

7. Apparatus as defined in claim 4 wherein said conveying means overlap each other in the axial direction, the overlapping end of each conveying means being inclined in approximate correspondence with the inclined support associated therewith.

8. Apparatus as defined in claim 7, the conveying means at the second wheel moving at greater speed than the conveying means at the first wheel.

9. Green decorticating apparatus of the class described comprising two upright scutching wheels rotating in opposite directions one behind the other, stationary arcuate scutching plates one extending around each wheel in its direction of rotation from points located approximately in the same axial line above the axes of the wheels, stationary arcuate supports one extending around each wheel from its scutching plate and in the opposite direction, the outer surfaces of said supports being at a greater radius from the axis of the machine than the scutching surfaces on the inner sides of said plates, intermediate radially inclined supports extending from the ends of each stationary support to points adjacent to and radially inward of said scutching surfaces, and laterally off-set and axially overlapping conveying means one extending axially over each stationary support.

10. Apparatus as defined in claim 9, said intermediate supports having substantially conical surfaces decreasing in radius from the stationary support at one wheel toward the other wheel and having a final radius less than that of the scutching surface at said other wheel.
